WALL MOUNTED SHOE HANGER

Deborah E. Sussman, 11632 San Vicente Blvd.,
Los Angeles, Calif. 90049

Filed Aug. 4, 1969, Ser. No. 18,513

Term of patent 14 years

Int. Cl. D6—01

U.S. Cl. D80—10

FIG. 1 is a perspective view of a wall mounted shoe hanger embodying my new design, the broken line representation of a shoe is for purposes of illustration only;

FIG. 2 is a side elevational view thereof;

FIG. 3 is a top plan view thereof;

FIG. 4 is an end elevation view, as viewed from the right of FIG. 1;

I claim:

The ornamental design for a wall mounted shoe hanger, as shown and described.
